UNITED STATES PATENT OFFICE

STEPHEN N. BUCHANAN, OF ELIZABETH, NEW JERSEY, ASSIGNOR TO THE THOMAS & BETTS CO., OF ELIZABETH, NEW JERSEY, A CORPORATION OF NEW JERSEY

FIXTURE SUPPORT

Application filed February 29, 1928. Serial No. 257,904.

This invention relates to electrical outlet box fittings such as fixture supports to attach lighting fixtures and the like to boxes and consequently relates to box fittings ordinarily called hickeys and studs which together make the fixture support. Box studs and hickeys are used to install or attach a lighting fixture, lamp or chandelier to a box in electrical house wiring work, and I have produced what may be called a slip or plug-in hickey and stud which are connected together by a slip-in action, instead of screw fastening them together as in the old fashioned way.

The load or weight of the electric lighting fixture is hung from the outlet box. Ordinarily a box stud is on the box when the mechanic approaches the job to hang a lighting fixture. The latter usually includes a fixture stem on the lower end of which is carried the electric lights or lamp fixture and on the upper end a fitting called a hickey is fastened. The old style hickey is screwed onto the fixture stem before the mechanic ascends his ladder or scaffold and hence is not in itself difficult to attach but it has been the practice for the mechanic to have to carry the load of the lighting fixture up the ladder and then feel for and find the threads of the box stud and then screw the hickey into the stud, all of which is difficult and tedious work. Furthermore the rotation of the lighting fixture to screw the hickey into the box stud causes the fixture wires to become snarled up and damaged, especially so when the wires are untwisted by the mechanic who pulls or jerks them out to unravel them.

As to the old style hickey mentioned in the foregoing paragraph, this part is a well known box fitting including two threaded hickey sleeve ends integrally formed on a wire receiving loop. This device is herein called a hickey because it is thus known to the trade and performs the purposes of attaching a fixture stem and hence the lighting fixture to a box and provides an outlet for the fixture wires which run up through the stem to a box B from a lighting fixture (not shown) on the lower end of the stem. My invention provides new and useful cooperat-

ing hickeys and studs as well as new parts and fittings accessory thereto, whereby the difficulty long experienced in screwing the upper hickey end to a box stud is entirely removed.

It is a general object to avoid the difficulties and to reduce the labor and render more convenient the installation of a lighting fixture and its connection to a box. To this end, I have produced a fixture support which includes a novel box stud and hickey so constructed and arranged that a plug-in or slip-in connection or anchorage is effected between these two parts and hence between the fixture stem carrying a lighting fixture and the box without making a screw fastened connection between the hickey and box stud. It is the elimination of this screw threaded connection which constitutes an important feature of this invention and which greatly simplifies the work.

A further object is to produce a fixture support box stud and hickey plug-in coupler embodying locking means, which may be spring actuated and hence automatic, and by which the hickey is positively locked and anchored to a box, but it is readily detached from the box stud to remove the lighting fixture from the wall or ceiling.

Another object is to produce essential adapter means by which present day old hickeys are refitted or converted to make them slip into my new box stud, and by which the old present day box studs are refitted or converted to make them receive my new hickeys. For the former use I have devised a hickey adapter and for the latter use a stud adapter.

A further object is to produce several forms of construction in accordance with the principles of this invention and to this end the accompanying drawings are presented to show several examples to meet and fulfill all possible uses arising between the various types of box fittings including different styles of boxes, fixture studs and hickeys. Accordingly I have devised several forms of box or fixture studs and hickeys, and I have produced a hickey adapter and a box stud adapter so as to make my invention useful with many old fittings which a building contrac-

tor may have on hand and hence may use in the box assembly and which the lighting fixture contractor may have on hand and hence may use in the lighting fixture assembly before fixing or installing the latter on the box.

Figures 1 through 4 illustrate the first form of the invention wherein all parts, i. e. my hickey and box stud, are new and are designed so as not to use any old fittings or adapters. Hence in this form of construction the well known box B is already fitted with my new box or fixture stud 15 when the workman comes to install an illuminating fixture.

Figure 1 is a box assembly view in section, showing the new hickey plugged into the new box stud, with a conduit attached to the box leading current supply wires thereto.

Figure 2 is a box and stud assembly view in section, and showing the new hickey in position ready to be plugged into the new box stud.

Figure 3 is a cross section on the line 3—3 of Figure 1 and hence through the novel hickey anchorage head and socket of the novel box stud.

Figure 4 shows a plan view of the base or foot of my new box stud as taken on the line 4—4 of Figure 2.

Figures 5 through 8 show hickey adapter means and illustrate the second form of the invention wherein the novelty is in the box stud and in a hickey adapter by which an old style hickey is used with the new style box stud 15 or 30, my novel hickey adapter 38 making this possible. Therefore a mechanic may gain the benefit of this invention and yet he may use old hickets. A lock nut may be used to remove looseness from all parts after they are assembled.

Figure 5 is a box assembly in section with the old style hickey attached to a hickey adapter, the latter being plugged into my new style socketed box stud.

Figure 6 is a view of a box and stud assembly, the hickey adapter with its attached parts being in position ready to be plugged into the new style box stud.

Figure 7 shows a perspective view of the hickey slip-in adapter made in the form of a support plunger. This hickey adapter means enables the workman to use old style hickets which he may have on hand with my new style box stud and secure all the conveniences of the invention.

Figure 8 is a plan view of the new box adapted to receive the hickey adapter shown in Figure 7 and is taken on the line 8—8 of Figure 6.

Figures 9 and 10 show a combination of two adapter means and illustrate a third form of the invention wherein an old style box stud 50 is converted into a new style socketed box stud by a stud adapter sleeve 52 and into which the hickey adapter of Figure 7 is received thus enabling the workman

to use an old hickey HS, or by which the new hickey 26 shown in the first form, is attached to an old box stud 50.

Figure 9 is a sectional box assembly wherein an old hickey is connected to an old box stud, this arrangement being brought about by employment of a box stud adapter of the general type as shown in Figure 12 and a hickey adapter as in Figure 7. A compression spring may be used to remove looseness from all parts after they are assembled, instead of a lock nut as in the second form.

Figure 10 shows a plan view of an old form of box stud, but which I convert to use with my invention by employing a stud adapter 52 to receive a hickey adapter 38, or to receive the new style hickey 26.

Figures 11, 12 and 13 illustrate a fourth form of the invention wherein my improved fittings and fixture support are adapted for use on cast boxes CB which ordinarily have integral threaded studs 60. For this form of cast box I again use a sleeve stud adapter 61 which screws onto the box stud and I thereby convert it into a socketed box stud so as to receive a new plug-in hickey 26, or to receive my new hickey adapter 38.

Figure 11 shows the cast box and stud in fragmentary section and a coil spring actuated locking plunger is provided to lock the hickey to the box stud adapter after the parts are connected by a plug-in action.

Figure 12 is a perspective view of the box stud adapter removed from all parts. An adapter of this general form refits an old box stud for use with my new slip-in hickey to secure all the advantages of this invention.

Figure 13 is a section on the line 13—13 of Figure 11.

Figures 14 and 15 illustrate the fifth form of the invention wherein my new slip-in hickey of the first form is slightly modified to provide combined peripheral and longitudinal grooves in the slip-in head of the hickey.

Figure 14 is a box assembly view, the stud and box being in section, and the modified hickey being in elevation.

Figure 15 is a view on the line 15—15 of Figure 14 showing the engaged box stud socket and hickey head in section.

In accordance with the principles of my invention, I have produced, among other things as above noted, two box fitting adapters. One may be called a box stud adapter and is used to convert the old style threaded box stud now in use to one which will receive my novel plug or slip-in hickey. In this way, an old type screw threaded stud may be left on the box, when found so fitted as in old house work, yet the workman may use my new slip-in hickey therewith. The other may be called a hickey adapter and is used to convert the old style two-threaded ended hickey to one which will plug into my novel

box stud. In this way, my new box stud may be left on the box, when found so fitted as in new house work, yet the workman may use up his old hickies and still effect a slip-in connection. Likewise I have produced a novel box stud which preferably should be fitted to outlet boxes so as to make direct connection with my new slip-in hickey and thus eliminate all necessity for either type of adapter means.

Electrical house wiring installations ordinarily embody electric outlet steel boxes B having knock-out openings or holes H to receive pipes or conduits P in which cable C runs into the box and in which the current supply wires W are connected with the fixture wires FW leading up through a fixture stem FS. Cast iron boxes CB are also used for certain classes of work and cable (not shown) is usually connected to this type of box to supply current to the lighting fixture wires FW. The lower end of the fixture stem FS supports a lighting or lamp fixture, say a chandelier and encloses the fixture wires FW. It is the usual practice to provide a hickey L, the lower sleeve end HS invariably being screw threaded to make connection with and support the fixture stem FS and a lighting fixture (not shown) on the lower end of the stem.

The screw threaded hickey sleeve lower ends HS are preferably of similar structure throughout the several examples of the invention, but vary in size and form for different work. On the other hand the remaining structural portions or upper ends of the hickies L are new and so constructed and arranged as to accomplish new results and effect a saving of labor on fixture installations regardless of the character of the box or box stud which may have been installed by the building contractor, and regardless of the type of hickey, new or old, which the lighting contractor may use. In this way, when the lighting fixture contractor approaches the job, he is equipped in all respects to use my invention.

Coming now to a description of the first form of the invention as shown in Figures 1 through 4, it may be remarked that this form includes a hickey L the upper end 26 of which is new and adapted to be plugged into a box stud 15 which is likewise new, and in this respect no old parts are used, and this form of the invention is therefore well suited for new house work, where no old electrical work or parts are encountered. The novel box stud includes an anchorage base, plate or foot 15 integral with a sleeve 16 which provides a slip-in hickey receiving socket 17. Screws or other means 14 anchor the stud to the box B in the usual way. This box stud 15-16 may be enlarged at 18 on one side of the sleeve so as to provide a plunger bore 19 for the reception of a locking plunger

20 which is slidably retained in the bore 19 so that the inner end 21 of the plunger protrudes into the stud sleeve 16.

One end of the locking plunger 20 is made with head or flange 25 by which the workman with his screw driver or by finger action withdraws the plunger end 21 from the sleeve socket 17 so as to disconnect the plug-in or slip-in hickey from the box stud 15. The base or foot 15 is grooved at 22 above the socket 17 and the plunger head 25 rests within this groove. A plate spring 23 has one end anchored at 24 to the box stud while its other end is flexibly free and normally lies in contact with the plunger head 25 to maintain the plunger end 21 in innermost limited position. The plunger end 21 is withdrawn from the stud socket 17 by overcoming the seating pressure of the spring 23 which is accomplished by lifting upward on the plunger head 21.

The bore 19 and locking plunger 20 are disposed at an angle to the axis of the hickey head 26 and stud sleeve 16 which position of the plunger enables an upward entering thrust of the hickey head 26 to push the locking plunger 20 out of the way or back out of the sleeve, the spring 23 yielding for this purpose so that the hickey may be plugged into the stud. Furthermore this angular position of the plunger presents a substantially long or maximum portion thereof to and against the hickey head 26 to positively anchor the latter in the stud sleeve 16. The downward pressure or pull of the hickey head 26, due to the weight of a lighting fixture, tends to firmly engage the hickey head and locking plunger one with the other. The angular interlocking action between the hickey plunger head 26 and the locking plunger 20 is a positive one.

The hickey used in connection with this first form of the invention includes the usual wire receiving loop L integrally formed with lower hickey sleeve HS and this formation HSL in box hickies are now in use but I have improved the upper end of the hickey by adding the slip-in plunger head 26 so as to make a plug-in connection between the hickey L and box stud 15 and hence avoid screwing the parts together as in the past. In this simple change, I have attained a new mode of action and a labor saving result without losing the benefit of the old form of well known hickey portions HSL which are in themselves well suited to attach to the fixture stem FS and expose the wires FW in the loop L.

The plug-in hickey head 26 is made with one or more locking plunger pockets or notches 27 for the reception of the plunger end 21. These notches 27 are disposed about the cylindrical surface of the slip-in head 26 and when the workman comes to install the lighting fixtures, he first screw connects the

hickey sleeve HS onto the fixture stem FS and thereafter he carries the lighting fixture (not shown) and stem FS with hickey L up a ladder or scaffold and plugs the hickey head 26 into the socket 17 of the box stud 15. This installation is accomplished without screwing the hickey L to the box stud 15 which is ordinarily the way the work has been accomplished in the past.

10 The old method of screwing a hickey to a box stud, say of the old type of stud shown at 50 in Figure 9 or at 60 in Figure 11, is laborious in that the workman is required to carry the weight of the lighting fixture, some 15 times very massive, up on a ladder and rotate the lighting fixture and supporting stem FS until the same is screw fastened to the stud 50 or 60 and box which has always been an arduous task in view of the fact that one must 20 locate and start the threads between the old style hickey and old style box stud. Furthermore the old method usually results in twisting or snarling up the fixture wires FW so that after the work of screwing the fixture 25 stem S into the box stud is accomplished it is then necessary for the workman to unwrap the wires thereby damaging the insulation.

In the drawings, the fixture wires FW and the lead-in wires W are shown as being of 30 somewhat short length but as a matter of fact they are left long in actual practice so that the electrician may make soldered and wrapped connections on the outside of the box B and he then pushes them up in the un- 35 obstructed portions of the box. However, by adoption of my invention this task of screw threading the stem FW into the box assembly as well as unwrapping the twisted up wires is avoided. Manifestly a great deal 40 of time is thus saved which reduces the labor cost in that the workman simply makes a quick slip-in connection between the fixture stem FS and the box B.

Coming next to a description of the second form of the invention shown in Figures 45 5 through 8, provision is here made for the use of old style hickeys HSL with a new type box stud 30 similar in many respects to the box stud 15 already described in the first 50 form. In this second form, there is shown in Figure 7 what may be called a hickey adapter which I have devised for affording a plug-in connection between the old hickey HSL and new box stud 30 or 15. In this way 55 the mechanic may use up the supply of old hickeys on hand with the new box stud assembly when the latter is used in the building.

To the box B is attached the box or fixture 60 stud 30 in the usual way as by screws 14. The stud 30 includes a sleeve 31 and a locking plunger bore 32 is formed at an angle in the sleeve so that a locking plunger 33 will slide up and down in the sleeve. A head 65 or flange 34 is made on one end of the lock-

ing plunger 33 and the other end of the plunger projects into the inside of the stud sleeve 31. The upper open end of the bore 32 proximate the plunger head 34 is peaned over at 35 to prevent the plunger 33 from dropping out. The indent or peaned portion 35 coacts with a flat surface 36 formed on the plunger 33 to slidably retain the same in the sleeve 31. This locking plunger 33 drops into place by its own weight and protrudes inside the sleeve 31.

70 The hickey adapter comprises a smooth plug-in plunger head upper end 38 with a threaded anchorage lower end 39. Locking pockets or notches 40 are formed in the surface of this adapter 38 and are engaged by the lower end of the locking plunger 33 or 21 when the adapter head 38 is slipped into the stud sleeve 31. The screw threads 39 of the hickey adapter attaches to the old type hickey L both ends of which are screw threaded at 85 HS since it has been the practice in the past to screw fasten one end of this hickey L to the fixture support FS and the other end HS to an old style box stud fastened within 90 an outlet box. Each end of the old hickey L is no more than a mere sleeve HS so designated to indicate the old type of hickey ends, which however may be used with my improved box parts simply by the employment 95 of the hickey adapter 38.

A lock nut 42 is screwed onto the hickey adapter end 39 and is tightened against the lower end of the stud sleeve 31 after the parts are assembled. By tightening the lock nut 42 it follows that the hickey adapter head 38 is forced into tight engagement with the locking plunger 33 thereby removing all play existing in the parts so that final anchorage is 105 effected, and no looseness may develop.

Describing the third form of construction in Figures 9 and 10, I have devised an adapter combination which permits the use of old 110 box studs and old hickeys. In this respect the structure in the third form constitutes a distinct advantage in that all old fittings may be used but at the same time the mechanic on the job is saved the difficulty of screw fastening the fixture stem FS to the box B by the old process of rotating the stem FS and lamps hanging on the lower end thereof while working on top of the ladder or scaffold.

115 The box B is here shown as being fitted with an old form of box stud 50 carried on a foot plate 51 and secured to the box in any approved manner. In some box installations the building contractor may have used this old type of box stud 50, and at the same time the lighting fixture contractor may desire to avail himself of the advantages of this invention and yet may himself be supplied with old hickey parts. Even so, I have provided in this situation a novel stud adapter 120 in the form of a sleeve 52 screw threaded at 125

70

80

85

90

95

100

105

110

115

120

125

130

one end to fasten it to the old style box stud 50 and open at the other end to effect a plug-in connection with the hickey adapter 38 or with the new style hickey L26 if the latter is available for use. In either case, the lower end HS of either type of hickey, old or new, is screw fastened to a fixture stem FS and up through which the fixture wires FW are lead toward the box B.

10 Instead of using the lock nut 42 heretofore described as in the second form, I here employ a compression spring 53 carried on the hickey adapter 38 between the lower end of the stud adapter sleeve 52 and the hickey sleeve HS which snaps or presses all the play out of the parts when the slip-in connection is made. A locking plunger 33 is carried with the stud adapter 52 to lock the hickey adapter 38, with all parts carried thereon, to the stud adapter 52 and hence the stem FS to the box. My new stud adapter 52 therefore converts the old box stud 50 to one which is in effect socketed so as to receive a hickey head whether of the integral kind shown at 25 26 or a separate adapter shown at 38. By combining the two adapters 38 and 52, the old box stud and old hickey are converted to simpler uses.

Coming to the fourth form of the invention as shown in Figures 11, 12 and 13, special provision is made for adapting my improvements to old style cast boxes CB which are provided with a cast fixture stud 60. Ordinarily it is the practice to use an old style hickey HS screw fastened to the old cast box stud 60, the disadvantages of which have been explained and the elimination of which is now made possible by working in accordance with the principles of this invention and adapting the parts supplied thereby.

In working with the old cast boxes CB, and aside from the precise illustration of Figure 11, the mechanic in fact may use the hickey adapter 38 of Figure 7 so as to attach the old hickey HS to the box CB which the reader may well imagine by reference to the second form Figure 5 or third form Figure 9 of the invention, since indeed I have provided a box stud adapter 61 which will receive and lock the hickey adapter 38 thereinto. The combination of both types of adapters 38 and 61 or 52 fulfill many uses and requirements.

In this fourth form, the new style slip-in hickey 26 is similar to or may be the same as the first form shown in Figure 1, and I have provided a stud adapter in the form of a sleeve 61 threaded at one end and open at the other end to receive the hickey plunger head 26. This adapter sleeve 61 is fitted with an angularly disposed locking plunger 62 which is urged to seated position by a coil spring 63 mounted between an integral ear 64 and the head or flange 65. This spring 63 holds the locking plunger 62 against and in 65 one of the hickey pockets 27 so that it is

anchored in the sleeve 61 against rotation and against removal except by withdrawal of the plunger 62.

The fixture stem FS and hickey L26 are first screw fastened together and the head 26 of the latter is plugged into the adapter sleeve 61, the locking plunger 62 yielding upwardly to permit the hickey head 26 to enter the sleeve, whereupon the mechanic rotates the stem FS until one of the pockets 27 is engaged by the lower end of the plunger 62. The fixture stem and box assembly is now completed and is effected without laboriously screw fastening the hickey to the box stud 60.

In the fifth form of the invention in Figures 14 and 15 there is shown a structure which is similar in some respects to the first form in Figure 1. However a box stud 70 is made with a hickey receiving socket 71 to receive a hickey head 72, the latter being formed if desired with plunger locking pockets 73 joining a peripheral locking groove 74. With this form of construction the mechanic simply plugs the hickey head 72 into the stud socket 71 and is not required to rotate the stem FP to hunt one pocket 73 since indeed the groove 74 instantly catches the lower end of a locking plunger 75. Nevertheless I may provide locking plunger pockets 73 to stop undue or accidental turning of a lamp fixture carried on the lower end of the stem FS.

In general, it is now clear to the reader that I supply means by which the advantages of this invention are attained regardless of what character of box or box stud is encountered. The first form of my invention is largely used for new and original house work. The second form is used for either since I show a box assembly which comprises the new box and stud assembly but an old hickey and fixture support stem.

The third and fourth forms show old box and stud assemblies often met with in old house work, but by use of the adapter shown in Figures 7 and 12, I easily reconstitute the old box work so that my slip-in hickey may be used. Therefore, the invention furnishes a means to meet all situations arising when a lighting contactor makes ready to install illuminating fixtures.

In the main, my new box stud comprises a receptacle socket to receive the plug-in head of the hickey, and the socket and head are preferably cylindrically-shaped parts and are easily manufactured and fitted together. The cooperating cylindrically-shaped parts are smooth surfaced. The locking device 120 possesses a bolt action, automatic in function when a spring is used as at 23 or 63, so by merely plugging the hickey head into a stud socket, the two parts are automatically locked together because the spring actuated locking plunger instantly returns and snaps into one 125 130

of the pockets or ratchets in the plug-in hickey head.

According to my novel principles involved in the production of box studs, as suggested by all forms, the stud is carried by the box, separately attached or integral therewith, and takes the form of sleeve-like means into which a plunger-like device is plug connected and this plunger carries the hickey and fixture stem.

Throughout all examples of the invention, the bolt-action locking plunger is similar in mode of operation to a spring pressed dog since the plungers 20, 33, 62 and 75 ratchet and lock against the ratchet detents 27 and 40 formed in the hickey heads. Any suitable resilient spring means may be used to actuate the locking bolt or dog and the spring is preferably placed outside of the hickey receiving socket of the box stud.

What is claimed is:

1. A fixture support comprising, in combination, a hollow fixture stud and means to secure same to an outlet box, a hickey carrying a slip-in head which plugs into the fixture stud, means for locking the head in the stud when plugged together, and means carried by one of the parts of the support and exerting a force against the stud tending to withdraw the head from the stud and serving to accentuate the action of the locking means.

2. A fixture support comprising, in combination, a hollow fixture stud and means to secure same to an outlet box, a hickey carrying a slip-in head with plugs into the fixture stud, means for locking the head in the stud when plugged together, and a nut threaded upon the slip-in head and engaging the end of the hollow stud thereby exerting a force against the stud tending to withdraw the

head therefrom and serving to accentuate the action of the locking means.

3. A fixture support comprising, in combination, a hollow fixture stud and means to secure same to an outlet box, a hickey carrying a slip-in head which plugs into the fixture stud, means for locking the head in the stud when plugged together, and a spring surrounding the head and exerting a force against the stud tending to withdraw the head from the stud and serving to accentuate the action of the locking means.

4. A fixture support comprising, in combination, a hollow fixture stud forming a socket and means closing one end of the socket and securing the stud to a box, a groove in the securing means above the socket, a plate spring secured at one end in the groove and the other end being flexibly free, and a locking plunger slidably mounted in the fixture stud and having one end projecting into the socket while the other end is engaged by the flexibly free spring end.

5. A fixture support comprising, in combination, a hollow fixture stud forming a socket, and means closing one end of the socket and securing the stud to a box, a groove in the securing means above the socket, a plate spring secured at one end in the groove and the other end being flexibly free, a locking plunger slidably mounted in the fixture stud and having one end projecting into the socket while the other end is engaged by the flexibly free spring end, and means carried by one of the parts of the support and exerting a force against the stud tending to withdraw the head from the stud and serving to accentuate the action of the locking means.

In testimony whereof I affix my signature.

STEPHEN N. BUCHANAN.
